UNITED STATES PATENT OFFICE.

BRUCE CLARK WHITE, DECEASED, LATE OF NEW YORK, N. Y.; BY MARIA LOUISA WHITE, EXECUTRIX, OF NEW YORK, N. Y.

ROTARY PRINTING PRESS.

Application filed August 28, 1924. Serial No. 734,666.

This invention relates generally to rotary printing presses of the type in which a rotary sheet carrier is arranged to present individual sheets to the printing rolls. The 5 present invention has more particular reference to the construction and operation of the sheet gripper devices with which the rotary carrier is equipped, the gripper device forming the subject matter of the present application being shown in part in a previous application for patent filed by Bruce C. White on April 18, 1922; Serial No. 554,886.

The present invention has for an object 15 to provide a novel and improved sheet gripper for the rotary carrier in which the gripper element is normally retained in gripping position by spring means, and is opened by a positive operating element 20 which is connected in common to a series of grippers while the spring closures thereof ensure of independent gripping action of each one of the series.

A further object of the invention is the 25 provision of a readily detachable mounting for the rock shaft which moves the grippers to open position, thereby facilitating replacement of any individual gripper, or series of grippers.

For further comprehension of the invention, and of the objects and advantages thereof, reference is had to the following description and accompanying drawing, and to the appended claims in which the 35 various novel features of the invention are more particularly set forth.

Fig. 1 of the drawings is a view showing the improved gripper as mounted on the carrier element, the gripper being shown 40 in side elevation, and the supporting bar and rock shaft in transverse section.

Fig. 2 is an elevational view at right angles to Fig. 1, one of the carrier rings being shown in transverse section.

Fig. 3 is a fragmentary horizontal sectional view taken on the line 3—3 of Fig. 1.

Fig. 4 is a fragmentary transverse sectional view taken on the line 4—4 of Fig. 2.

Fig. 5 is a detailed perspective view showing the manner of connecting to its end

elements the removable intermediate portion of the rock shaft which operates the grippers.

Fig. 6 is a fragmentary side view showing a slightly modified construction of 55 gripper jaw connections.

In printing presses of the type to which the invention is designed for application, the rotary sheet carrier comprises a pair of rings spaced axially from one another and 60 rigidly united by a series of cross bars, these cross bars serving also as supports for the sheet grippers.

In Figs. 1 and 2 of the drawing I have indicated at 10 a portion of one of the rings 65 of the sheet carrier, which latter is commonly referred to generally as the carrier ring, one of the cross bars being indicated at 11, these cross bars being commonly called gripper bars. My improved gripper 70 comprises a finger 12, which is fixed at one end to the inner face of the bar 11 and which projects transversely to the latter. A movable finger 13 co-operates with the finger 12, this finger 13 being located outward of the fixed finger 12 and having pivotally attached thereto, a relatively short distance from its gripping end, the free 75 ends of a pair of short, rigid, links 14 whose opposite ends are pivotally connected so to the fixed finger 12, on which latter the links 14 are arranged to swing. The movable finger 13 normally extends at an angle to the fixed finger 12, and to cause their contiguous faces to make substantially flat 80 contact with each other at the ends thereof, where the sheet is gripped, these end portions on the respective fingers are oppositely bevelled as shown.

The opposite end of the movable finger 90 13 is pivotally connected to a short arm on a rock shaft 16 extending along the rear or following side of the bar 11 and supported in bearing blocks such as 17 removably secured to said bar as by the screws 18. This 95 arm consists simply of a collar 20 which freely encircles the shaft 16 and which is extended or thickened at one side as shown at 20', this extension being of rectangular form. This extension 20' is formed with 100

a pair of threaded borings through which pass set screws 22 which bear at their inner ends on the flat bottom wall of a transverse groove or recess 23 cut in the shaft 16. 5 The movable gripper finger 13 is pivotally attached to the element 20', adjacent one corner thereof by means of a headed pin or projecting stud 24 which may be conveniently held in place by passing one of the 10 screws through a transverse groove or recess in said pin.

The shaft 16 is utilized to open the gripper finger 13 which latter is moved to, and held in closed position by means of an expansion spring 26 which surrounds a rod 27 which has one end forked as at 28 to straddle the said finger and which is pivotally attached thereto co-axially with the links 14. The spring 26 bears at one end 15 against the enlarged fork end 28 of the rod 27 and at its other end against a guide bracket 29 for the rod. This bracket 29 is fixed to the bar 11 and has an aperture therein through which the rod 27 passes 20 with a sufficiently loose fit to permit of slight angular movement of the rod with respect to the bracket. In the operation of the gripper the shaft 16 is rocked at the appropriate time by a suitable cam in the 25 direction indicated by the arrow in Fig. 1 of the drawing. As will be apparent from the relative disposition of the parts, this movement of the shaft will cause the point of the gripper finger 13 to be both moved transversely away from the fixed finger 12 and also drawn backward from the point of 30 the fixed finger.

To facilitate changing or adjusting any 40 of the grippers when desired the main length of the shaft 16, which carries the grippers and is supported by the bearing blocks 17, is detachably connected with opposite end portions which are rotatively supported by the rings of the sheet carrier, one of these 45 end portions being shown at 16'. As here shown the main length of shaft is flattened on opposite sides at its end as at 31 while the shaft elements 16' are formed at their ends with complementary recesses 32. By 50 withdrawing the connection screws 11' the cross bar 11 together with its connected shaft and gripper parts may be readily removed as a unit from between the opposite carrier rings 10, and in their removal the flattened shaft ends will slide through the 55 recesses 32 of the shaft elements 16'.

In Fig. 6 of the drawing I have indicated 60 slightly modified construction in which the links 14 are omitted and the movable finger 35 is of angular form and is pivotally connected at one end to the fixed finger. Connected to this finger 35 at its apical portion is one end of a rigid link 36 whose opposite end is arranged for connection to the 65 part 20' similarly to the connection of the

finger 13 as above described while the forked lower end of the rod 27 connects to the finger 35 co-axially with the link 36.

Having thus described the invention what I claim as new and desire to protect by 70 Letters Patent of the United States is as follows:

1. A sheet gripper for a rotary sheet carrier comprising a fixed finger, a movable finger co-operating therewith, a rock arm, means for pivotally connecting said arm to the inner end of said movable finger, means providing a swinging fulcrum mounting for said movable finger between its ends, a spring urging said movable finger to gripping position, and means for releasing said movable finger by the movement of said rock arm. 75

2. A sheet gripper for a rotary sheet carrier comprising a fixed finger, a movable finger co-operating therewith, a rock shaft, an arm adjustably fixed to said shaft to vary the gripping action of said movable finger, means for pivotally connecting said arm to the inner end of said movable finger, means for providing a swinging fulcrum mounting for said movable finger between its ends, a spring urging said movable finger to gripping position, and means for releasing said movable finger by the movement of said rock shaft. 80

3. A sheet gripper for a rotary sheet carrier comprising a fixed finger, a movable finger co-operating therewith a detachably mounted rock shaft, an arm adjustably fixed to said rock shaft to vary the gripping action of said movable finger, means for pivotally connecting said arm to the inner end of said movable finger, means for providing a swinging fulcrum mounting for said movable finger between its ends, and a spring urging said movable finger to gripping position. 100

4. A sheet gripper for a rotary sheet carrier comprising a fixed finger a movable finger co-operating therewith, means providing a swinging fulcrum mounting for said movable finger between its ends, a spring urging said movable finger to gripping position, a rock shaft, and an arm on 110 said rock shaft connected to said finger to move the same to releasing position.

5. A sheet gripper for a rotary sheet carrier comprising a fixed finger, a movable finger co-operating therewith, means providing a swinging fulcrum mounting for said movable finger between its ends, a spring urging said movable finger to gripping position, a rock shaft, and an arm on 120 said rock shaft connected to said finger to move the same to releasing position and a pair of screws threaded into the hub of said arm and engaging said shaft to operatively connect the shaft to the arm. 125

6. A sheet gripper for a rotary sheet 130

carrier comprising a fixed finger, a movable finger, a pair of links pivotally connected at the opposite ends to said fixed finger and movable finger near the gripping ends thereof, a rock shaft, an arm on said rock shaft connected to the other end of the movable finger to move the latter to open position, and a spring urging said movable finger to closed position.

10 7. A sheet gripper for a rotary sheet carrier comprising a fixed finger, a movable finger, a pair of links pivotally connected at opposite ends to said fixed finger and movable finger near the gripping ends thereof, a rock shaft, an arm on said rock shaft connected to the other end of the movable finger to move the latter to open position, a spring urging said movable finger to closed position, and a slideable rod connected at one end to said movable finger and around which said spring is coiled.

8. In sheet gripping means for a rotary sheet carrier, a gripper bar, a gripper operating shaft extending along said bar, said shaft comprising an intermediate portion, and end portions separately connected to said intermediate portion, and bearing blocks carried by said bar and supporting said intermediate portion.

9. In sheet gripping means for a rotary sheet carrier having a pair of oppositely spaced rings, a gripper bar detachably secured at its ends to said rings, a gripper operating shaft extending along said bar, said shaft comprising an intermediate portion rotatably mounted on said bar, and end portions of said shaft rotatably mounted in said spaced rings and separably connected to said intermediate portion.

10. In sheet gripping means for a rotary sheet carrier having a pair of oppositely spaced rings, a gripper bar detachably secured at its ends to said rings, a gripper operating shaft extending along said bar, said shaft comprising an intermediate portion detachably mounted for rotation on said bar, and end portions of said shaft rotatably mounted in said spaced rings and separably connected to said intermediate portion.

Signed at New York in the county of New York and State of New York this 12th day of August, A. D. 1924.

MARIA LOUISA WHITE,
*Executrix on the Estate of Bruce Clark
White, Deceased.*
